United States Patent Office

Des. 193,367
Patented Aug. 7, 1962

193,367

HAND HOLD

Everard C. Mersereau, 775 Hyslip Ave., Westfield, N.J.

Filed Nov. 22, 1961, Ser. No. 67,644

Term of patent 14 years

(Cl. D66—2)

Fig. 2.

Fig. 1.

Fig. 3.

Fig. 4.

Fig. 5.

FIG. 1 is a side elevational view taken from one end of a hand hold showing my new design;

FIG. 2 is a rear elevational view thereof;

FIG. 3 is a front elevational view thereof;

FIG. 4 is a top plan view thereof; and

FIG. 5 is a perspective view thereof.

I claim:

The ornamental design for a hand hold, as shown.
